J. E. HIGNUTT, OF DENTON, MARYLAND.

Letters Patent No. 72,294, dated December 17, 1867.

—
CINDER-SHOVEL.
—

The Schedule referred to in these Letters Patent and making part of the same.

TO ALL WHOM IT MAY CONCERN:

Be it known that I, J. E. HIGNUTT, of Denton, in the county of Caroline, and State of Maryland, have invented a new and improved Shovel for Removing Cinders from Coal-Stoves; and I do hereby declare the following to be a full, clear, and exact description of the same, reference being had to the accompanying drawing, which is made a part of this specification, and which represents a perspective view of my improved shovel.

The subject of my invention is a scoop-shaped shovel formed with teeth or bars, and a vertical or nearly vertical handle, to adapt it to conveniently remove the unconsumed cinders from a coal-stove or grate.

In the drawing, A represents the handle, rising in a vertical or nearly vertical position from the back, B, from the lower edge of which the teeth C C C project horizontally, the said teeth being either straight or curved, as may be necessary to adapt the shovel for use with any of the customary forms of coal-stoves. D D represent two side pieces, to adapt the utensil to contain a larger quantity of coal and convey it without spilling.

The form of the handle and other parts may be varied as occasion requires, without departing from the essential features of my invention.

Having thus described my invention, what I claim as new, and desire to secure by Letters Patent, is—

The cinder-shovel herein described, constructed with a vertical handle, A, and a horizontal or nearly horizontal toothed scoop, C D, substantially as and for the purpose set forth.

To the above specification of my improved cinder-shovel, I have signed my hand, this ninth day of May, 1867.

J. E. HIGNUTT.
